UNITED STATES PATENT OFFICE.

THOMAS L. CROOK, OF HICKSVILLE, OHIO.

TOOL HANDLE.

Application filed September 21, 1925. Serial No. 57,504.

This invention relates to handles for use in connection with forks, rakes, files or other tools or implements that may be provided with a shank or tang for insertion 5 into a socket in the handle.

The object of the invention is the provision of simple and efficient means in connection with the socketed tang-receiving end of a tool handle to initially hold and guide a tool tang 10 in predetermined relation to the handle while being inserted and driven therein.

The invention is fully described in the following specification, and while in its broader aspect it is capable of embodiment in 15 numerous forms, one embodiment thereof is illustrated in the accompanying drawings, in which,—

Figure 1 is a perspective view of a hay fork with the handle partly broken away 20 and disconnected from tool. Fig. 2 is an enlarged fragmentary side elevation of a tool and its handle with the handle partly in longitudinal section and with the tool tang initially held for insertion into the handle 25 socket. Fig. 3 is a similar view with the handle and tool in operative engagement. Fig. 4 is a view similar to Fig. 2 with the parts partly turned around, and Fig. 5 is a fragmentary view of the handle and tool in 30 complete assembled relation, and Fig. 6 is an outer end view of the ferrule member embodying the invention.

Referring to the drawings, 1 designates a tool handle, customarily of wood, and having the axially disposed tool-tang receiving 35 socket 2 in its inner end, 3 the usual reinforcing ferrule that is fitted on the inner socketed end of the handle, and 4 a cap member in which the present invention particularly resides and which is fitted over the outer end of the ferrule 3.

The tool 5, in the present instance, is represented as a hay fork provided with the usual tang 6 that is squared in cross-section 45 for insertion into the round socket or tang-receiving hole 2 of the handle. It will be understood that when the tang 6 is forced into the handle socket 2, the corner edges of the tang cut into the wall of the socket 50 and resist a withdrawal of the tang therefrom.

The cap 4 is provided crosswise of its outer or closed end with the usual slot 7 for receiving the cross bar portion 8 of the 55 tool when the tang is driven home into the handle, and in order that the tool may be

properly positioned in an angular relation with respect to the handle so that the tool will hang properly with respect to the handle should the latter be of the bent type, 60 as in the case of a pitchfork, the cap is frictionally positioned on the ferrule 3 of the handle with its cross slot 7 in right-angular relation to the plane of bend of the handle, or it may have any other predetermined relation to the handle suitable to the handle bend or the tool to be applied. When the handles are sold for extra handles or for replacement purposes, they are usually furnished by the factory with the ferrule 3 and 65 cap 4 attached. The cap, however, is not ordinarily so securely attached to the ferrule but what it may be easily knocked off if desired.

The side edge walls of the cap slot 7, in 75 carrying out the feature of my invention, are provided with inturned integral lips 9, which are preferably of greater width lengthwise of the slot 7 than the width of the tool tang 6 and are adapted to coat with 80 the opposite sides of the tang to frictionally grip the same and act as guides for holding the tang in aligned relation to the handle socket 2. The lips 9 are inclined inwardly toward each other, so that the width of the 85 space between the outer edges thereof is at least as great as the width of the tang end to be inserted therein, while the space between the inner or free ends of the lips is less than the width of the tang end so that the lips 90 will be slightly spread apart by the tang as it is forced inwardly therebetween. The metal of the cap has sufficient spring to cause them to have a yielding frictional engagement with the tang as it is forced therebetween through the cap slot.

If the handle is of the straight type, so that it is not important to secure the tool to the handle in any particular angular relation thereto, the lips 9 engage the tang of 100 the tool and assist in guiding and holding it in centered relation to the handle socket 2 while being forced therein. Should the tool be of a character requiring a bent handle, the tang of the tool may be initially inserted between the lips 9 and held thereby while the person doing the fitting can balance the handle and tool or sight along the handle to see if it is in proper angular relation thereto before forcing the tang into the handle 105 socket. If the handle does not bear the proper relation, the tool is removed from

between the lips 9 and the cap 4, then loosened on the ferrule 3 and turned thereon to obtain the proper relation of the cap slot with respect to the handle. This being 5 done, the tool tang is again inserted between the holding lips 9 and held thereby while the workman is determining if the tool is in proper relation to the handle. When the proper relationship of the handle and tool 10 has been obtained, the tool tang is forced into the socket 2 in the usual or any suitable manner and during such operation, or at least the initial portion thereof, the lips 9 serve as a guiding means for the tang. 15 The cap enclosed end of the handle 1 is shown, in the present instance, as provided with a countersink 10 in coaxial relation to the socket 2, so that when the tang is inserted between the lips 9 and in engagement 20 with the end of the handle, it may be easily and quickly centered with relation to the handle, as is apparent.

It is apparent that the provision of the 25 lips 9 on the cap, in addition to serving as guides for the tool tang 6, also reinforce the cap at the sides of its slot or opening 7 so as to prevent denting or other injury from rough usage. It frequently occurs 30 that a person in handling the handles 1 with the caps 4 attached will drop the cap enclosed end onto a pavement or cement floor or will drive the cap onto the end of the handle by striking it against a hard object. 35 Such usage will dent in the cap and it is found that the provision of the tongues 9 is sufficient to reinforce the cap to prevent injury from such usage.

I wish it understood that my invention 40 is not limited to any specific construction, arrangement or form of the parts, as it is capable of numerous modifications and

changes without departing from the spirit of the claims.

Having thus described my invention, what I claim as new and desire to secure by 45 Letters Patent is:

1. A tool handle having a tool-tang receiving socket in its end, and a cap mounted on the socketed end of the handle with its outer end spaced from the handle end, the 50 cap having a transverse slot in its outer closed end with tang guiding lips at the side edges of the slot and projecting toward the handle end.

2. A tool handle having a tool tang 55 receiving socket in its inner end, a cap mounted on the socketed end of the handle and having a tang receiving opening in register with the handle socket and spaced outwardly therefrom, said cap having integral lips 60 projecting into said space from opposite edge walls of the opening to form a space therebetween, which space is inwardly narrowed to a width less than that of the tool tang to be inserted therein whereby the lips 65 are forced apart by the tang and guide its entrance into the handle socket.

3. A tool handle having a tool-tang receiving socket in its inner end and having such end dished in concentric relation to 70 such socket to allow a tang to be easily centered therein, and a cap mounted on the socketed end of the handle with its outer end spaced from the handle end, the cap having provision for the insertion of a tool 75 tang therethrough and for guiding and gripping the tang preparatory to and during its insertion into the handle socket.

In testimony whereof I have hereunto signed my name to this specification.

THOMAS L. CROOK.
